JOHN A. HAGERSTROM, OF NEW YORK, N. Y.

TYPE-WRITING MACHINE.

No. 810,202.

Specification of Letters Patent.

Patented Jan. 16, 1906.

Application filed March 10, 1905. Serial No. 249,370.

REISSUED

To all whom it may concern:

Be it known that I, JOHN A. HAGERSTROM, a citizen of the United States, and a resident of the city of New York, borough of Brooklyn, in the county of Kings and State of New York, have invented a new and useful Improvement in Type-Writing Machines, of which the following is a full, clear, and exact description.

10 The purpose of the invention is to provide a construction of type-levers and a manner of pivoting them whereby each type lever or bar will have an extended bearing, insuring accuracy in printing action and stability in 15 all positions, the bearings being so constructed that while extended the type bars or levers can be arranged the conventional distance apart, all striking at a common center.

20 A further purpose of the invention is to so pivot the type bars or levers that their bearings can be quickly, conveniently, and positively adjusted to take up lost motion.

25 The invention consists in the novel construction and combination of the several parts, as will be hereinafter fully set forth, and pointed out in the claims.

30 Reference is to be had to the accompanying drawings, forming a part of this specification, in which similar characters of reference indicate corresponding parts in all the figures.

35 Figure 1 is a perspective view of a portion of the support for the type bars and levers and sundry of the type-bars and their bearings. Fig. 2 is a sectional plan view of the 40 parts shown in Fig. 1; the section being taken horizontally through the lower portions of the type-levers. Fig. 3 is a vertical section taken practically on the line 3 3 of Fig. 2, the view being drawn upon an enlarged scale. Fig. 4 is a detail vertical section taken practically on the line 4 4 of Fig. 3, and Fig. 5 is a detail section taken substantially on the line 5 5 of Fig. 3.

45 A represents the supporting-plate for the type-bars B, and C the alining-rail against which the type-bars rest when in their vertical position or position of rest. The supporting-plate A is preferably provided with four rows of apertures 10, 11, 12, and 13, the 50 first three named apertures being threaded and the aperture 13 plain, said latter aperture being adapted to receive pins 14. The apertures 10, 11, 12, and 13 are shown arranged in radial rows.

55 The apertures 10 are adapted to receive tap-screws 15, which extend a desired dis-

tance above the supporting-plate A, and the apertures 11 at one side of the center of the plate A are adapted to receive screws 16, having tapering head-sections 16^a, which are a 60 desired distance above the said supporting-plate A, while the apertures 12 at the other side of the center of the said plate A are adapted to receive similar screws 17. The screws 15 are bearing-screws and the screws 65 16 and 17 adjusting-screws. A bearing-plate 18 is provided for each bearing-screw, having its inner end 18^a upwardly curved, so as to extend beyond the inner edge of the supporting-plate, as is shown in Figs. 1 and 2. 70 Each bearing-plate is provided with a projection 19 from one of its side faces, being produced about centrally between the ends of the bearing-plate, as is best shown in Fig. 2. Each bearing-plate 18 is further provided at 75 the same side with a semicircular offset 20, the said offset being located between the projections 19 and the curved inner ends of the bearing-plates. The bearing-plates 18 are placed radially upon the supporting-plate A 80 adjacent to the rear of the apertures 10, 11, 12, and 13, and semicircular depressions in the bearing-plates formed by the offsets are each made to receive the head portion of a bearing-screw 15. The outer end portion of 85 each bearing-plate is made to engage with the corresponding side of a pin 14. Thus an adjusting-screw 16 or 17, as the case may be, is placed in an aperture 11 or 12, so that its head will bear against the projection 19 of 90 the bearing-plate to which said adjusting-plate is assigned, as is shown in Figs. 1 and 2.

The type-bars B each consist of a straight body-section 21, to the outer end of which the type 21^a is secured, and a base-section 95 which comprises an arched member 22 and foot members 23, which foot members extend diagonally in opposite directions from the ends of the arched member, and the outer ends of the foot members are given a straight 100 bend, forming toe extensions 24. When the type-bars B are in position, their arched members 22 are at right angles to the supporting-plate A, as is shown in Fig. 1, and are in horizontal alinement; but spaced a 105 suitable distance apart, and their toe members 24 are pivoted to the most convenient bearing-plates 18, the pivoting of the type-bars being such that the arched member of one type-bar will straddle the foot members 110 of several of the other bars, as is shown in Figs. 1 and 2.

The type-bars are pivoted in the following manner: The toe extensions 24 are provided with conical indentations 25, and the upwardly-curved inner ends 18^a of the bearing-plates 18 have conical projections 26, which enter the said indentations, as is shown in Fig. 5, so that should lost motion occur at the pivotal connection of each type-bar with its bearing a speedy and effective remedy is found by simply lowering one or the other of the adjusting-screws 16 or 17 used in connection with the particular type-bar, thereby forcing one of the bearing-plates 18 in direction of its mate, and thus tightening the connection between the bearing-plates and the toe extensions of the type-bars.

In the arrangement of the bearing-plates two of them must necessarily come together at one point in a circular supporting-plate A, as is shown at C in Figs. 1 and 2, and in such position of the bearing-plates the offset portions 20 of both bearing-plates 18 engage with one post or screw 15, but at opposite sides, and likewise engage with opposite sides of one pin 14, which is in alignment with said post or screw 15. But two adjusting-screws 16 or 17 are employed, engaging with the outer faces of the bearing-plates 18, one adjusting-screw being located in the series of apertures 11 and the other in the series of apertures 12.

The two series of apertures 11 and 12 are employed because in practice it has been found best to have the adjusting-screws engage the right-hand sides of the bearing-plates 18 at one side of the center of the supporting-plate C and the left-hand side of the bearing-plates 18 at the other side of the center of the said supporting-plate.

Under the above-described construction it is obvious that an extended bearing is provided for each type-bar, rendering said bars more accurate in action and giving them more solidity and that any lost motion may be speedily and conveniently taken up.

Having thus described my invention, I claim as new and desire to secure by Letters Patent—

1. In type-writing machines, a pair of independent bearings, independent guide-supports and adjusting devices for each bearing, and a type-bar having an arched lower ex-

tremity, and foot members extending in opposite directions from and at an angle to the terminals of said arched extremity, each 55 foot member having an independent pivotal connection with one of said bearings.

2. In type-writing machines, a pair of bearings, guide-supports, adjusting devices for the same, and a type-bar having a lower 60 arched member and foot members extending horizontally in opposite directions from the ends of the arched member, which foot members are pivoted in said bearings.

3. In type-writing machines, a support, 65 bearing-plates in pairs located on said support, adjusting devices for the bearing-plate, a type-bar having an arched lower member radially disposed with reference to the support, horizontal oppositely-disposed foot 70 members extending from the ends of the arched member, toe extensions from the foot members, and pivotal connections between the bearing-plates and the toe extensions of the type-bar.

4. In type-writing machines, a supporting-plate, bearing-posts and pins carried by the supporting-plate and arranged in transverse rows, bearing-plates in pairs located upon the supporting-plate, said bearing-plates 80 having semicircular offsets for engagement with the bearing-posts, their inner ends being upwardly curved beyond the inner edge of the supporting-plate, the outer ends of said bearing-plates having engagement with said 85 pins, said bearing-plates being also provided with projections from one side face and with conical offsets at their curved inner ends, and type-bars having arched lower members radially disposed to the supporting-plate, and oppositely-extending horizontal foot members at the ends of the arched members, each foot member having a toe extension provided with a depression to receive the offsets from the inner ends of the bearing-plates, 90 and adjusting-screws engaging with the projections on the bearing-plates, as described.

In testimony whereof I have signed my name to this specification in the presence of two subscribing witnesses.

JOHN A. HAGERSTROM.
